 Hixon-Keiser Patents Corporation, New York,
 N. Y., a corporation of New York

Application February 18, 1933, Serial No. 657,414

16 Claims. (Cl. 179—6)

This invention relates to sound recording and reproducing apparatus and has special reference to an automatic telephone message receiver and recorder.

5 Devices have been invented for the purpose of automatically receiving and recording messages in connection with a subscriber's telephone instrument but hitherto such devices have necessitated conductive connection between the wiring 10 of the telephone system and the apparatus for such reception and recording. For various reasons not necessary here to discuss, such direct connection to the telephone circuits is objectionable and the operating companies generally refuse 15 to allow the use of such apparatus.

One important object of the present invention is to provide a novel arrangement of apparatus for this purpose wherein there is no conductive electrical connection between the telephone circuits and the circuits involved in the invention 20 so that the device may be installed without in any way interfering with the present telephone installations.

In my prior application for patent on an Automatic telephone message receiver and recorder, filed on September 20, 1932 and bearing the Serial Number 634,025, now Patent No. 1,973,081, granted Sept. 11, 1934, I have described an apparatus in which the initiation of the sequence of operations 25 in the device is established through the effect of sound waves. While this apparatus constitutes a marked advance in the art over those devices conductively or mechanically connected to the telephone system it has been found that it has 30 a tendency to start operating from causes other than the ringing of a telephone bell. For instance, it has been found that the operation of an air hammer such as is used in riveting during the erection of steel structures will, under certain conditions, initiate the operation cycle.

A second important object of the present invention is to provide an improved device of this character wherein the operation cycle will be initiated by the electrical impulses associated with 45 the ringing of the call bell and wherein sound will have no effect in initiating such cycle of operations.

A third important object of the invention is to provide a novel arrangement of such apparatus whereby the telephone instrument remains in normal condition with the receiver hook depressed or (in so called "French" type telephones) with the mouth and ear piece on the stand except during the reception of the message, the apparatus being arranged to automatically lift the hook

or mouth and ear piece immediately after initiation of operation and to allow the hook to drop or the mouth and ear piece to be seated upon conclusion of the operation.

A fourth important object of the invention is 5 to provide a novel pick-up arrangement for use with a subscriber's telephone equipment to receive impulses from the electro-magnetic or electro-static field occurring in the vicinity of all parts of such equipment and to cause such impulses to 10 effect operation of the call answering apparatus and the message receiving apparatus comprising parts of this invention.

A fifth important object of the invention is to 15 provide an improved answering means for use in such apparatus.

A sixth important object of the invention is to 20 provide an improved means for lifting the movable part of a subscriber's telephone instrument to establish the telephone talking circuit.

A seventh important object of the invention is to 25 provide a novel arrangement of electrical circuits and controls for use in connection with an apparatus of this character.

With the above and other objects in view, as 30 will be presently apparent, the invention consists in general of certain novel combinations of elements and arrangements of parts hereinafter fully described, illustrated in the accompanying drawings and specifically claimed.

In the accompanying drawings like characters of reference indicate like parts in the several views, and:—

Figure 1 is a general diagrammatic view of one 35 form of the invention showing the wiring thereof.

Figure 2 is a detail wiring diagram illustrating 40 a modification of certain parts of the arrangement of Figure 1.

Figure 3 is a semi-diagrammatic detail showing 45 one arrangement of pick-up as used herein.

Figure 4 is a view similar to Figure 3 but showing 50 a second arrangement of the pick-up.

Figure 5 is a view similar to Figure 3 but showing 55 a third arrangement of the pick-up.

Figure 6 is a view showing a modified pick-up 40 operating electrostatically.

Figure 7 is a view showing a fourth form of 45 field pick-up.

Figure 8 is a view showing a form of pick-up 50 wherein the call box casing is employed as means actuated by the electro-static field to form the pick-up.

Figure 9 is a view of a modified electro-magnetic 55 field pick-up employing a sound detector.

Figure 10 is a view showing a pick-up adapted

for use with the transmitter of a "French" type telephone instrument.

Figure 11 is a view similar to Figure 10 but showing an arrangement for use with the standard type of telephone instrument.

Figure 14 is a plan view partly in section of the telephone lifting and speaking elements of this invention.

Figure 15 is a front elevation, partly in section of the apparatus shown in Figure 14.

Figure 16 is a section on the line 16-16 of Figure 14.

Figure 17 is a section on the line 17-17 of Figure 14.

Figure 18 is a section on the line 18-18 of Figure 14.

In the general embodiment of the present invention as shown in the main wiring diagram illustrated in Figure 1 there is disclosed certain standard equipment which includes the bell or call box 10 and transmitter 11 which are commonly used in telephone systems and which here represent such parts of a telephone system. This call box and transmitter form no part of the present invention and are here shown in order that the manner of utilizing the invention in conjunction with such a system may be fully understood. Also there is indicated at 12 an ordinary audioamplifier. The construction of such amplifiers is old and well known and it is not deemed necessary here to disclose the details of the amplifier since such details form no part of the present invention. All such amplifiers have input, output and power connections and in this case the power lines 13 and 14 are shown connected to the amplifier by wires or other conductive connections 15.

At 16 is a pick-up which may be either of the electro-magnetic type or the electro-static type and is in no way conductively or physically connected to any part of the telephone system. For the purposes of this application this pick-up will be termed a field actuated pick-up and it is to be understood that this term means a pick-up actuated solely by a field which may be either electro-magnetic or electro-static and which has no physical nor conductive connection with any part of the telephone system proper. This pick-up is conductively connected to the input of the amplifier by conductors such as the wires 17. The pick-up is shown in this figure as arranged adjacent the box 10 to receive the stray field which surrounds the box whenever the ringing or talking circuit of the telephone line is operated. However, it is to be understood that a field pick-up for this purpose may be located anywhere adjacent the telephone lines or apparatus since all such lines and apparatus are surrounded by stray fields. Thus, for the purposes of this invention it is merely necessary that the pick-up be located somewhere in the field of the telephone system.

Leading from the output end of the amplifier are conductor wires 18 and 19. The wire 18 is connected to one terminal of the primary winding of a transformer 20 and the wire 19 is connected to the other terminal of this primary through a variable resistance 21. At 22 is a three element tube having the usual filament, grid and

plate. One terminal of the transformer secondary is connected to the grid of the tube by a wire 23. The wire 14 is connected to one terminal of the filament by a wire and resistance 24 and the wire 13 is connected to the other terminal of the filament by a wire 25 having a resistance 26 interposed therein. The other terminal of the transformer secondary is connected by a wire 27 to a variable contact on the resistance 26.

A relay magnet 28 has one terminal connected to the plate of the tube 22 by a wire 29 and its other terminal connected by a wire 30 with the wire 14, a condenser 31 being bridged across the wires 29 and 30. This magnet 28 actuates an armature contact 32 to cause this contact to engage a fixed contact 33 upon energization of the magnet 28 and the fixed contact 33 is connected by a wire 34 with the wire 14. The contact 32 is connected by a wire 35 with one terminal of a relay magnet 36 which has its other terminal connected by a wire 37 with the wire 13. The armature 38 for this magnet is a heavily loaded spring armature which vibrates between two fixed contacts 39 and is connected by the wire 40 with the wire 14. The armature 38 is so proportioned and loaded that, after de-energization of the magnet 36 this armature will continue to alternately engage the contacts 39 for a predetermined time period, for instance, four seconds. The contacts 39 are connected in multiple by a wire 41 with one terminal of a relay magnet 42 and the other terminal of this magnet is connected by a wire 43 with the wire 13. The magnet 42 carries on the armature end of its core, a heavy single turn of copper 44, a so-called "slug." The magnet 44 is then, in effect, a transformer with a short-circuited secondary of extremely low resistance. When the circuit is closed for the primary coil of the transformer, and the current begins to rise, and the core begins to be magnetized, a comparatively heavy current is induced in the copper "slug" 44. This current in the "slug" in turn produces its own magnetic field but in a direction opposite to the magnetic field produced by the current in the primary coil. The effect of the "slug" 44 is therefore to produce a lag in the magnetization of the core of this magnet 42. The action is similar when the circuit of the primary is opened, and in this case, the effect is to retard the demagnetization. In short, the purpose of the "slug" 44 is, in effect, to introduce a large magnetic reluctance in the circuit of the magnet only for the time during which the current in the magnet coil is either rising or falling. This produces a "slow-moving" relay action and the "slug" 44 constitutes a reluctance coil or winding. An armature 45 is moved by energization of this magnet 42 into engagement with a fixed contact 46 which is connected by a wire 47 with the wire 14. The arrangement of the armature 45 and contact 46 is preferably of the vacuum contact type. A wire 48 connects the armature 45 with a relay armature 49 which normally engages a fixed contact 50.

A motor 51 has one terminal connected by a wire 52 with the contact 50 and the other terminal of this motor is connected by a wire 53 with the wire 13. The motor 51 drives a mandrel 53 whereon is mounted a phonographic record 54 having recorded thereon speech to the effect that no person is present at the receiving subscriber's station and that any message spoken will be recorded. A sound box 55, equipped with the usual reproducer needle, is caused to traverse the record by a screw 56 driven by the motor 51.

through suitable gearing. A small tone horn 57 is connected to this sound box and rests beneath the transmitter 11. The horn 57 is connected to the sound box in a manner hereinafter described and is movable independently of the sound box. As is well known, it is necessary, to establish the talking circuit of the telephone to lift the telephone hook in the standard form of telephone or the combined receiver and transmitter in the so called "French" form. The horn 57, resting beneath the instrument is movable to effect such lifting by means of a solenoid 58 which has its core connected to one arm of a lever 59 carrying the horn 57 so that upon energization of the solenoid the horn, and consequently the movable part of the telephone instrument, is lifted. One terminal of the solenoid 58 is connected to the wire 48 by a wire 81 and the other terminal of the solenoid is connected by a wire 60 with the wire 53, the solenoid thus being initially in multiple with the motor 51. Normally, by means hereinafter described, the needle of the sound box is held normally out of contact with the record 54 and out of feed screw control by means hereinafter described in detail, such means including a magnet 62 which, when energized, brings the needle into contact and the feed arrangement into service. The magnet 62 is connected by a wire 63 with the wire 52 and by a wire 64 with the wire 53, being thus in multiple with the motor. A spring 65 normally holds the sound box at the starting end of the record 54.

On the screw 56 is a nut or carriage (see Fig. 14) carrying a movable contact 66 which is fed along by the screw 56 until, at the time the needle reaches the end of the record, it contacts with a fixed contact 67. The contact 66 is connected by a wire 68 with the wire 48 and the contact 67 is connected by a wire 69 with a contact 70 and with one terminal of the relay magnet 71 which controls the armature 49 and which has its other terminal connected by a wire 72 to the wire 13. The magnet 71, when energized, moves the armature 49 into engagement with the contact 70 and with a contact 73, breaking the contact at 50 simultaneously. The contact 73 is connected by a wire 14 with one terminal of a motor 75 having its other terminal connected by a wire 76 with the wire 53. This motor 75 drives the mandrel 77 of a phonographic recording device having the usual recording sound box 78 and the mouth piece 79 connected acoustically thereto. A speaker unit 80 confronts this mouth piece and is connected by wires 81 with the wires 18 and 19.

Inasmuch as the general operation of the invention can be well understood from the figure just described it is though well to describe this general operation before entering into any description of modifications or details of construction. In order to make clear the operation it is assumed that the device is in use at a telephone subscriber's station with no one present to answer the instrument. A call is sent through the telephone system for this station. There is, of course, primarily a signal which produces a field causing the field pick-up 16 to function and the current from this pick-up passes to the amplifier 12 over the wires 17. These current impulses are amplified in the amplifier which is constantly receiving power over the wires 15 from the power lines 13 and 14. Amplified impulses issue from the amplifier over the wires 18 and 19 and a predetermined portion of these impulses pass to the transformer 20 and thence to the tube 22. Due, in this

form of the connections, to the biasing of the grid circuit only the positive impulses affect the plate circuit and thus effect a series of impulses through the magnet 28 which causes a succession of closings of the armature 32 on the contact 33. This, in turn, causes a series of energizations of the magnet 36. Each time the armature 32 closes on the contact 33, the magnet 36 is energized, and the armature 38 is drawn all the way over, making connection with the front contact 39. When this contact 38 39 is made, the magnet 42 is energized, drawing over the armature 45 and closing the contact 45 46. When the armature 32 is released, the contact 32 33 is opened, and the magnet 36 is de-energized. The armature 38 is released, but, due to its construction as a vibrator, it vibrates and alternately makes contact with the front and back contacts 39. This sends a series of current impulses through the magnet 42. These vibrations of the armature 38, and consequently the impulses of current, persist for an adjustable time, say four seconds, and due to the special arrangement of this magnet core, these magnetizing impulses are sustained, the armature 45 is held over and the contact 45 46 remains closed, until the vibrations of armature 38 die down and the armature 38 comes to a standstill and the contacts 38 39 are positively opened. It is therefore evident that for every momentary closing of the contact 32 33, the contact 45 46 will remain closed for any preadjusted time afterward, say four seconds. Current will now flow from the wire 14 through wire 47, contact 46, armature 45, wire 48, armature 49, contact 50, wire 52, motor 51 and wire 53 to wire 13. Simultaneously, the solenoid 58 and magnet 62 will be energized, these being, as previously described, in multiple with the motor. The solenoid 58 will lift the movable part of the telephone instrument and establish the talking circuit and the magnet 62 will pull the needle down into contact with the record 54 driven by the motor. The record will then "speak" and the person calling will be informed of there being no one present and that a message may be spoken and will be recorded. As the end of this message is reached the contact 66 engages the contact 67 and current will flow from line 13 through wire 72, magnet 71, wire 69, contact 67, contact 66, wire 68, wire 48, armature 45, contact 46 and wire 47 to the line 14. This will energize the magnet 71 which will attract the armature 49, break the contact at 50 and establish contact at 70 and 73. Since the contact is broken at 50 current will no longer be supplied to the motor 51 and solenoid 62. The motor will stop, the needle of the reproducer 55 will lift off the record and the reproducer nut will disengage from the screw and be restored to starting position by the spring 65, thus restoring the contact 66 to initial position as will be later explained. The calling subscriber may now speak any message he desires into his telephone. The current impulses due to his speech will continue to affect the tube 22 and thus act to hold the armature 45 in engagement with the contact 46. Current will continue to flow through the solenoid 58 and current will also flow from the line 13 through wire 72, magnet 71, contact 70, armature 49, wire 48, armature 45, contact 46 and wire 47 to the line 14. The magnet will thus hold the armature in engagement with contacts 70 and 73 so that current will also flow from line 13 through wire 53, wire 76, motor 75, wire 74, contact 73, armature 49, wire 48, armature 45, contact 46 and wire 47 to line 14. The motor 75 will now operate and im-

pulses due to any message spoken by the calling subscriber will be picked up by the pick-up 18 and be transmitted to the input end of the amplifier. The amplified message impulses will be 5 transmitted from the amplifier over the wires 18 and 19 and the wires 31 to the speaker unit 80 where they will be transformed into sound waves and be transmitted through the horn 79 to the recording unit 78 which acts to cut the record 82 10 in accordance therewith thus recording the spoken message. When the calling subscriber ceases talking there will no longer be a succession of impulses affecting the tube 22 so that the armature 32 will remain out of engagement with 15 the contact 33. This will effect continuous de-energization of the magnet 36 so that the amplitude of vibration of the armature 38 will decrease until it no longer touches the contacts 39 whereupon the magnet 42 will de-energize and contact 20 will be broken between the armature 45 and contact 46. This breaks both the circuit of the motor 77 and the circuit of the solenoid 58 so that the motor 77 stops and the movable part of the telephone instrument is restored to the normal position 25 to break the talking circuit and establish a ringing circuit. Also the magnet 71 is de-energized and the armature 49 reengages the contact 50. Thus the device is set ready for a second operation. It is to be understood that the armature 30 38 is so proportioned and loaded that some time, say four seconds, will elapse after de-energization of magnet 36 before this armature ceases to engage the contacts 39. Consequently a momentary cessation of speech by the calling subscriber will not cause stoppage of the motor or 35 restoration of the ringing circuit. Obviously, if the calling subscriber does not care to leave a message the motor and solenoid circuit will be broken as just described upon completion of the message 40 to him after lapse of the time for which the armature 38 is set.

In the modification disclosed in Figure 2 the wiring and other parts are identical with what is shown in Figure 1 except in certain particulars 45 which will now be described. The wire 21 is replaced by a wire 21' which is connected directly to the power line 13. A wire 83 leads from the plate of the tube 22 to one terminal of the primary winding of a transformer 84 and the other 50 terminal of this primary winding is connected by a wire 85 with the wire 14. The secondary winding of this transformer 84 has its terminals connected to the terminals of the magnet 28 by wires 86.

55 In Figures 3 to 5 a pick-up coil adapted to be affected by the electro-magnetic field around the telephone equipment is shown at 87, the coil being arranged above the call box in Figure 3, below the box in Figure 4 and on one side of the box in Figure 5.

In Figure 6 the pick-up is shown as a plate 88 and in Figure 7 is a coil 89, these parts being affected by the field in the vicinity of the call box.

In Figure 8 the metal casing of the box itself 65 is used as an electro-statically energized pick-up.

In Figure 9 a sound detector 90 of the electro-dynamic type is connected by wires 91 to a coil 92 inductively associated with the pick-up coil 83 connected to the amplifier intake as usual.

70 Figures 10 and 11 show electro-magnetic pick-up coils 94 and 95 adapted for insertion of the receiver of a "French" and standard telephone instrument respectively.

In Figures 12 and 13 is shown an electro-static pick-up consisting of a plate 96 whereon the tele-

phone instrument may be set, a "French" telephone being shown in Figure 12 and a standard telephone being shown in Figure 13.

Considering now the constructional details shown in Figures 14 to 18 inclusive it will be seen that there is provided a casing 97 wherein is located the motor 51, solenoids 58 and 62, mandrel 53 and speaker record 54, sound box 55 and other parts associated therewith.

The solenoid 58 supports a bracket 98 to the upper end of which the lever 59 is fulcrumed intermediate its ends. The solenoid core is attached to one end of this lever and from the other end of the lever depends a link 99 carrying at its lower end a bar 100 provided with collars 101 at 15 its ends. The horn 57 extends through the front wall of the casing and is connected by a flexibly jointed sound tube 102 with the reproducer box 55. As here shown the arrangement has been made for a "French" telephone instrument having a base B and transmitter-receiver TR. When in position the mouth of the horn 57 lies below one end of the part TR and an idle horn 103 has its mouth below the other end of this part and extends into the casing 97 to a universal 25 jointed support 104. The collars 101 surround the necks of the horns 57 and 103 and, when the solenoid 58 is energized the mouth ends of the horns and the instrument TR are lifted thereby breaking the calling circuit of the telephone and 30 establishing the talking circuit. In order to permit adjustment of the solenoid to obtain proper lifting movement of the instrument TR this solenoid is supported between brackets 105 by screws 106 passing through vertical slots 107 35 in said brackets.

The motor 75 drives a counter-shaft 108 through a speed reducing drive 109 and the counter-shaft drives the mandrel 53 through a speed reducing drive 110. The screw 56 is driven from 40 the counter-shaft by a drive 111. Over the sole-noid 62 extends a lever 112 pivoted at one end to a bracket 113 mounted on an end wall of the casing 97. The core of the solenoid 62 is connected to the lever at about the middle thereof and the 45 other end of the lever is provided with a yoke which straddles the reproducer box 55. This box is provided with pins 114 which pass through slots 115 formed in the yoke arms. A tension spring 116 has its lower end attached to the lever 112 50 and its upper end attached to the top of the casing 97 and normally holds the reproducer needle clear of the record 54. Extending from the reproducer box is an arm 117 carrying at its free end a half-nut 118 which is normally held raised 55 above the screw 56 but which, upon energization of the solenoid 62, is moved down into engagement with the screw as shown in the detail figures. Attached to the arm 117 is one end of the restoring spring 65 and the other end of this 60 spring is attached to a suitable post in the casing. The nut 118 carries the contact 66, this contact being, of course, insulated from the nut. The contact 67 is mounted on the casing wall in the path of the contact 66 when the nut is in engagement with the screw.

From the operation as previously described it will be clear that upon a signal being picked up the solenoids 58 and 62 will be energized and the motor 51 started. The solenoid 58 will cause the 70 instrument TR to lift and establish the talking circuit. At the same time the solenoid 62 will pull down the lever 112 and bring the reproducer needle into engagement with the record 54 and the half-nut into engagement with the 75

screw 56. The reproducer will now be fed across the record, this being permitted by reason of the pin and slot connection between the reproducer box 55 and lever 112. The contact 66 moves with the half-nut and, when the record 54 has finished talking, engages the contact 67. This effects energization of the change over magnet 71, breaks the circuits through the motor 51 and solenoid 62 as previously described. The spring 116 now lifts the horn 112 and the spring 65 restores the reproducer box 55, half-nut 118 and contact 66 to normal starting position.

For the purpose of making the language of the claims clear certain legends have been placed upon Figure 1 of the drawings and it will there be seen that the first three relays are termed "sustaining relays" and the fourth relay is termed a "change over relay".

There has thus been provided a simple and efficient device of the kind described and for the purpose specified.

It is obvious that many minor changes may be made in the form and construction of the invention without departing from the material principles involved. It is not, therefore, desired to confine the invention to the exact form herein shown and described but it is desired to include all forms which properly come within the scope of the appended claims.

Having described my invention, I claim:

1. In apparatus of the class described, a field pick-up, an amplifier to which said pick-up delivers current impulses, sustaining relays and circuits therefor receiving current from said amplifier, a speaking record, a recorder, electro-motive means for operating the speaking record and recorder, a change-over relay receiving current through one of said sustaining relays and including an electro-magnet, a normally closed circuit receiving current through the change-over relay and arranged to cause the electro-motive means to actuate the speaking record upon energization of the sustaining relays, a change-over circuit supplying said relay magnet with current upon completion of the operation of said speaking record, and a normally open circuit receiving current through the change-over relay and arranged to cause the electro-motive means to cause actuation of the recorder, the normally closed circuit being opened and the normally open circuit being closed upon energization of the said relay magnet.

2. In apparatus of the class described, a field pick-up, an amplifier to which said pick-up delivers current impulses, sustaining relays and circuits therefor receiving current from said amplifier, a speaking record, a recorder, electro-motive means for operating the speaking record and recorder, a change-over relay receiving current through one of said sustaining relays and including an electro-magnet, a normally closed circuit receiving current through the change-over relay and arranged to cause the electro-motive means to actuate the speaking record upon energization of the sustaining relays, a change-over circuit supplying said relay magnet with current upon completion of the operation of said speaking record, a normally open circuit receiving current through the change-over relay and arranged to cause the electro-motive means to cause actuation of the recorder, the normally closed circuit being opened and the normally open circuit being closed upon energization of the said relay magnet, and circuit means closed by the energization

of said relay magnet and arranged to maintain energization of the magnet during energization of the sustaining relays.

3. In apparatus of the class described, a field pick-up, an amplifier having its input connected to said field pick-up, sustaining relays and circuits therefor actuated by current output from the amplifier, a speaking record, a motor for actuating said speaking record, a recorder, a second motor for actuating said recorder, a motor circuit for each of said motors, a change-over relay including an actuating electro-magnet, the circuits controlled by said change-over relay being supplied with power upon energization of the sustaining relays, said change-over relay normally closing the first motor circuit and opening said first motor circuit and closing the second motor circuit upon energization of said magnet, and means actuated by the first motor to close a circuit through said magnet upon completion of the operation of the speaking record.

4. In apparatus of the class described, a field pick-up, an amplifier having its input connected to said field pick-up, sustaining relays and circuits therefor actuated by current output from the amplifier, a speaking record, a motor for actuating said speaking record, a recorder, a second motor for actuating said recorder, a motor circuit for each of said motors, a change-over relay including an actuating electro-magnet, the circuits controlled by said change-over relay being supplied with power upon energization of the sustaining relays, said change-over relay normally closing the first motor circuit and opening said first motor circuit and closing the second motor circuit upon energization of said magnet, means actuated by the first motor to close a circuit through said magnet upon completion of the operation of the speaking record, and circuit means closed by the energization of said relay magnet and arranged to maintain energization of the magnet during energization of the sustaining relays.

5. In apparatus of the class described, a field pick-up, an amplifier having its input connected to said field pick-up, sustaining relays and circuits therefor actuated by current output from the amplifier, a speaking record, a motor for actuating said speaking record, a recorder, a second motor for actuating said recorder, a motor circuit for each of said motors, a change-over relay including an actuating electro-magnet, the circuits controlled by said change-over relay being supplied with power upon energization of the sustaining relays, said change-over relay normally closing the first motor circuit and opening said first motor circuit and closing the second motor circuit upon energization of said magnet, means actuated by the first motor to close a circuit through said magnet upon completion of the operation of the speaking record, circuit means closed by the energization of said relay magnet and arranged to maintain energization of the magnet during energization of the sustaining relays, electro-magnetic means controlled by one of said sustaining relays and arranged to lift a telephone instrument to establish its talking circuit, and means for conveying sound impulses from the talking record to the telephone instrument.

6. In apparatus of the class described, a field pick-up, an amplifier having its input connected to said field pick-up, sustaining relays and circuits therefor actuated by current output from the amplifier, a speaking record, a motor

- for actuating said speaking record, a recorder, a second motor for actuating said recorder, a motor circuit for each of said motors, a change-over relay including an actuating electro-magnet, the 5 circuits controlled by said change-over relay being supplied with power upon energization of the sustaining relays, said change-over relay normally closing the first motor circuit and opening said first motor circuit and closing the second 10 motor circuit upon energization of said magnet, means actuated by the first motor to close a circuit through said magnet upon completion of the operation of the speaking record, circuit means closed by the energization of said relay magnet 15 and arranged to maintain energization of the magnet during energization of the sustaining relays, electro-magnetic means controlled by one of said sustaining relays and arranged to lift a telephone instrument to establish its talking circuit, and means for conveying sound impulses from the talking record to the 20 telephone instrument.
9. In apparatus of the class described, a field 10 pick-up, an amplifier having its input connected to said field pick-up, sustaining relays and circuits therefor actuated by current output from the amplifier, a speaking record, a motor for actuating said speaking record, a recorder, a second 15 motor for actuating said recorder, a motor circuit for each of said motors, a change-over relay including an actuating electro-magnet, the circuits controlled by said change-over relay being supplied with power upon energization of the 20 sustaining relays, said change-over relay normally closing the first motor circuit and opening said first motor circuit and closing the second motor circuit upon energization of said magnet, means actuated by the first motor to close a circuit 25 through said magnet upon completion of the operation of the speaking record, circuit means closed by the energization of said relay magnet and arranged to maintain energization of the magnet during energization of the sustaining relays, said recorder having a sound receiving horn 30 associated therewith, a speaker unit connected to the output of the amplifier and confronting said sound receiving horn, electro-magnetic means controlled by one of said sustaining relays and arranged to lift a telephone instrument to establish its talking circuit, a reproducer box and needle movable to bring the needle into and out of engagement with the speaking record, and electro-magnetic means in parallel with the first motor and arranged to cause engagement of the needle and record upon energization of said first motor and to cause lifting of the needle out of said engagement upon opening of the circuit for the first 35 motor.
7. In apparatus of the class described, a field 30 pick-up, an amplifier having its input connected to said field pick-up, sustaining relays and circuits therefor actuated by current output from the amplifier, a speaking record, a motor for actuating said speaking record, a recorder, a second 35 motor for actuating said recorder, a motor circuit for each of said motors, a change-over relay including an actuating electro-magnet, the circuits controlled by said change-over relay being supplied with power upon energization of the 40 sustaining relays, said change-over relay normally closing the first motor circuit and opening said first motor circuit and closing the second motor circuit upon energization of said magnet, means actuated by the first motor to close a circuit through said magnet upon completion of the operation of the speaking record, circuit means closed by the energization of said relay magnet and arranged to maintain energization of the magnet during energization of the sustaining relays, said recorder having a sound receiving horn 45 associated therewith, a speaker unit connected to the output of the amplifier and confronting said sound receiving horn, electro-magnetic means controlled by one of said sustaining relays and arranged to lift a telephone instrument to establish its talking circuit, a reproducer box and needle movable to bring the needle into and out of engagement with the speaking record, and electro-magnetic means in parallel with the first motor and arranged to cause engagement of the needle and record upon energization of said first motor and to cause lifting of the needle out of said engagement upon opening of the circuit for the first 50 motor.
10. In apparatus of the class described, an audio-frequency amplifier, sustaining relays and circuits therefor connected to the output of said amplifier, a field actuated pick-up conductively connected to the input of said amplifier and being located adjacent a telephone line but without any physical or conductive connection with said line, said pick-up being adapted to receive the currents emanating from the telephone line whenever the ringing or talking circuit of said 55 line is operated and to utilize said currents to operate said sustaining relays through the intermediary of said amplifier, a translating device connected to the output of said amplifier, a recorder associated with said translating device, a motor for actuating said recorder, and a motor circuit for said motor to which power is supplied upon energization of the sustaining relays, said sustaining relays being adapted to maintain the supply of power to said motor circuit for a predetermined time subsequent to the cessation of energization of the sustaining relays.
11. In apparatus of the class described, a field 60 pick-up, an amplifier to which said pick-up delivers current impulses, sustaining relays and circuits therefor actuated by current output from said amplifier, a translating device connected to the output of said amplifier, a recorder associated with said translating device, a motor for actuat- 65 70 75 80 85 90 95 98 99

ing said recorder, and a motor circuit for said motor to which power is supplied upon energization of the sustaining relays, said sustaining relays being adapted to maintain the supply of power to said motor circuit for a predetermined time subsequent to the cessation of energization of the sustaining relays.

12. In apparatus of the class described, a field pick-up, an amplifier to which said pick-up delivers current impulses, sustaining relays and circuits therefor actuated by current output from said amplifier, a recorder, said recorder having a sound receiving horn associated therewith, a speaker unit connected to the output of said amplifier and confronting said sound receiving horn, a motor for actuating said recorder, and a motor circuit for said motor to which power is supplied upon energization of the sustaining relays, said sustaining relays being adapted to maintain the supply of power to said motor circuit for a predetermined time subsequent to the cessation of energization of the sustaining relays.

13. In apparatus of the class described, an amplifier having its input coupled to a telephone line, a translating device connected to the output of said amplifier, a recorder associated with said translating device, a speaking record, electro-motive means for operating the speaking record and the recorder, sustaining relays and circuits therefor actuated by current output from said amplifier, a change-over relay receiving current through one of said sustaining relays and including an electro-magnet, a normally closed circuit receiving current through the change-over relay and arranged to cause the electro-motive means to actuate the speaking record upon energization of the sustaining relays, a change-over circuit supplying said relay magnet with current upon completion of the operation of said speaking record, and a normally open circuit receiving current through the change-over relay and arranged to cause the electro-motive means to cause actuation of the recorder, the normally closed circuit being opened and the normally open circuit being closed upon energization of the said relay magnet.

14. In apparatus of the class described, an amplifier having its input coupled to a telephone line, a translating device connected to the output of said amplifier, a recorder associated with said translating device, a speaking record, a motor for actuating said speaking record, a second motor for actuating said recorder, a motor circuit for each of said motors, sustaining relays and circuits therefor actuated by current output from said amplifier, a change-over relay including an actuating electro-magnet, the circuits controlled by said change-over relay being supplied with power upon energization of the sustaining relays, said change-over relay normally closing the first motor circuit and opening said first motor circuit and closing the second motor circuit upon energization of said magnet, and means actuated by the first motor to close a circuit through

said magnet upon completion of the operation of the speaking record.

15. In apparatus of the class described, an amplifier having its input coupled to a telephone line, a translating device connected to the output of said amplifier, a recorder associated with said translating device, a speaking record, a motor for actuating said speaking record, a second motor for actuating said recorder, a motor circuit for each of said motors, sustaining relays and circuits therefor actuated by current output from said amplifier, a change-over relay including an actuating electro-magnet, the circuits controlled by said change-over relay being supplied with power upon energization of the sustaining relays, said change-over relay normally closing the first motor circuit and opening said first motor circuit and closing the second motor circuit upon energization of said magnet, means actuated by the first motor to close a circuit through said magnet upon completion of the operation of the speaking record, circuit means closed by the energization of said relay magnet and arranged to maintain energization of the magnet during energization of the sustaining relays, electro-magnetic means controlled by one of said sustaining relays and arranged to lift a telephone instrument to establish its talking circuit, and means for conveying sound impulses from the talking record to the telephone instrument.

16. In apparatus of the class described, an amplifier having its input coupled to a telephone line, a translating device connected to the output of said amplifier, a recorder associated with said translating device, a speaking record, a motor for actuating said speaking record, a second motor for actuating said recorder, a motor circuit for each of said motors, sustaining relays and circuits therefor actuated by current output from said amplifier, a change-over relay including an actuating electro-magnet, the circuits controlled by said change-over relay being supplied with power upon energization of the sustaining relays, said change-over relay normally closing the first motor circuit and opening said first motor circuit and closing the second motor circuit upon energization of said magnet, means actuated by the first motor to close a circuit through said magnet upon completion of the operation of the speaking record, circuit means closed by the energization of said relay magnet and arranged to maintain energization of the magnet during energization of the sustaining relays, electro-magnetic means controlled by one of said sustaining relays and arranged to lift a telephone instrument to establish its talking circuit, a reproducer box and needle movable to bring the needle into and out of engagement with the speaking record, and electro-magnetic means in parallel with the first motor and arranged to cause engagement of the needle and record upon energization of said first motor and to cause lifting of the needle out of said engagement upon opening of the circuit for the first motor.

MORRIS KEISER. 65
